UNITED STATES PATENT OFFICE.

WILLIAM H. HALL, OF CICERO, ILLINOIS.

VACUUM CARPET-CLEANER.

1,077,603.

Specification of Letters Patent.

Patented Nov. 4, 1913.

Application filed April 2, 1912. Serial No. 688,093.

To all whom it may concern:

Be it known that I, WILLIAM H. HALL, a citizen of the United States, and a resident of Cicero, Cook county, Illinois, have invented certain new and useful Improvements in Vacuum Carpet-Cleaners, of which the following is a specification.

The primary object of the invention is to provide a practical light running, easily emptied and easily manipulated vacuum carpet cleaner, particularly adapted for household use.

In one practical embodiment of my invention the vacuum producing device, preferably of the bellows type, is carried by a bellows base hinged to the body of the machine and a one-piece dust-pan and nozzle combined. A detachable yielding connection with the body is removably mounted adjacent the vacuum device, the air chamber of the machine being formed by an air-tight connection between the bellows base and the one-piece dust-pan and nozzle, the dust-pan itself providing the side and bottom walls and the bellows base the top wall of said air chamber. The bellows base is adapted to swing back on its hinges to permit the free and easy removal of the combined dust-pan and nozzle for the purpose of cleansing, while the machine remains standing in its normal position on the floor.

The novel construction of the dust-pan and nozzle and its yielding connection with the machine permits the main body of the machine to rest entirely on wheels, thus insuring a light running machine, and the novel manner of creating the air chamber eliminates close fitting air-tight joints between hard rigid substances liable to injury and consequent leakage, and also obviates the necessity of disconnecting such joints and the consequent disagreeable disturbance of the dust when emptying the machine. The integrally constructed dust-pan and nozzle may accordingly be removed from the machine and the dust accumulated on the nozzle as well as that in the pan may be carried to a suitable place and deposited without scattering it over the floor.

Referring to the drawings which illustrate a preferred embodiment of my invention:—Figure 1 is a side elevation showing the machine as it stands on the floor, provided with the usual forked handle for its operation; Fig. 2 is a rear view with the rear wall of the bellows chamber removed; Fig.

3 is a side elevation with the near-side walls removed. In this figure the dotted diagram shows the position of the bellows chamber when thrown back for the purpose of removing the dust-pan; Fig. 4 is a front view of the machine with the front wall removed and with the bellows chamber thrown back in the position indicated in Fig. 3; Fig. 5 is a plan view of the dust-pan showing a flange of leather or other air tight yielding material attached to the top edge of the pan, by means of which a yielding air-tight connection is made between the dust-pan and the body of the machine, and Fig. 6 is an enlarged detail of a yielding lock or holder for holding the bellows chamber in air-tight connection with the leather flange around the top of the dust-pan.

On the drawings A B C indicate the bellows chamber in which two bellows G G' are mounted. These bellows are operated by crank and pitman connections D and D'—see Fig. 2. The cranks are rigidly mounted on the shaft E and on this shaft the drive wheel F is rigidly mounted. As will be seen in Figs. 1 and 3 the rear end of the machine rests entirely on this wheel, and in order to give it a considerable circumference and driving power it is extended upward between the bellows, G and G'.

Mounted on the under side of the bellows chamber, at the rear end, are two brackets H and H'. See Figs. 2 and 3. These brackets are hung in line and the shaft E passes through them—see Fig. 2—and they are the hinges on which the bellows chamber swings back as shown in Fig. 3.

The body of the machine, aside from the bellows chamber, is a box-like frame, one side wall of which is indicated by the letter I, Fig. 1. On the rear end of this box-frame, or body, are mounted two brackets J and J'. See Figs. 1 and 2. The shaft E passes through these and supports the rear end of the machine. The front end of the machine is supported on two smaller wheels K and K', see Figs. 1, 3 and 4. The sides of this body are held together by the front wall L and two cross pieces or partitions L' and L''—see Fig. 3. The partition L' is set far enough back to form a frame or compartment for holding the dust-pan and nozzle M and M' respectively. This pan and nozzle are made in one piece, either integral construction or rigidly connected parts, the lower portion of the front wall of the body

of the machine being cut away to allow the nozzle M' to extend out slightly in front of the machine. It will be evident by reference to Fig. 3 that when the bellows chamber A B C is thrown back in the position shown by the dotted lines in this view, the top of the compartment holding the dust-pan will be entirely open and the pan and nozzle may be freely lifted out without jar-
 5 ring or disturbing the dust. It will also be observed that the machine will be left standing in its natural position on the floor, and that no tight fitting joints have been disconnected or other members removed, in
 10 order to get the dust-pan out.
 The dust-pan is connected with the machine and the air chamber is formed in the following manner: The compartment for the dust-pan M is preferably somewhat
 15 larger than the pan, as will be seen by reference to Fig. 3. The top of the dust-pan has secured thereto a peripheral flange of leather or other suitable air-tight yielding material, preferably cut a little larger than
 20 the inside measurement of the compartment provided for the dust-pan, and provided near its margin with a number of eyelet-holes. In the top of the walls of the dust-pan compartment are a number of pins—
 25 indicated by O and O' in Fig. 4 and O'' in Fig. 3—corresponding in position to the eyelet-holes, and when the dust-pan is lowered into the compartment these pins pass through the eyelet-holes and hold the
 30 leather flange in position. In the baseboard A C of the bellows chamber are also a number of holes—shown as small circles near upper margin and on sides in Fig. 4—which correspond in position to these pins, and
 35 when the bellows chamber is lowered into closed position the pins enter the holes and the base of the chamber rests firmly on the leather flange holding it securely in position, and in combination with the dust-pan
 40 this baseboard forms the air chamber, the sides and bottom of the pan forming the sides and bottom of the air chamber and the base of the bellows A C forming the top of the air chamber.
 45 The port-holes Q and Q' of the inhaling valves of the bellows, Figs. 3 and 4, open into the air chamber thus formed, and to protect the bellows from the dust drawn into this chamber by the exhausting of the
 50 air therefrom through the medium of the bellows I employ a dust-screen mounted on a frame Q'', Fig. 4. This frame and screen, which may be of any desired size, is preferably slidably mounted on the lower face of
 55 the bellows' base so that it may be easily removed. The screen may be similarly mounted on a removable frame fitted into the top of the dust-pan if desired but preferably it is mounted on the bellows base as
 60 shown.
 65

The leather flange attached to the top of the dust-pan and held securely against the walls of the compartment by the base of the bellows chamber, allows more or less free movement of the pan within the compartment, but it is desirable that relative horizontal movement between the pan and frame be prevented so that the nozzle may move promptly with the machine as it travels rapidly back and forth over the floor. To this end a pair of brackets P, Fig. 3, is attached to the rear wall L' and on the rear end of the pan M, and forming an integral part thereof, are two twin hangers or brackets P' each having a V-shaped notch on the lower side adapted to fit over the upturned part of the brackets P attached to the wall when the pan is lowered into the compartment. This connection permits a rocking motion of the pan independent of the body of the machine and allows vertical movement of the nozzle so that it may adjust itself to the thickness of the rug or carpet over which it travels. It will not, however permit of any backward or forward movement of the nozzle and pan independently of the machine and therefore insures the prompt movement of the nozzle in unison with the backward and forward movement of the machine.

To insure an air-tight connection between the leather flange attached to the top of the dust-pan and the bellows' base and walls of the compartment, a lock is provided on the front end of the machine, an enlarged detail of which is shown in Fig. 6. A U-shaped bracket R is secured to the inside of the front wall. A bolt S passes through the two arms of the bracket and has an expansion spring T mounted thereon between the arms. A pin or collar is fixed to the bolt below the spring so that when the bolt is pulled upward by means of the knob S' the spring will be compressed. The bolt is free to turn, and near the upper end is a pin X which normally is just below the top surface of the bellows chamber when it is in position. In the middle of the front end of the bellows chamber and registering with this bolt is a slot Y. See Figs. 3 and 4. When closing down the bellows chamber the pin X is turned parallel with the slot, and when the chamber has been brought down to position, the bolt S is pulled upward against the spring until the pin X is above the surface of the roof of the chamber and then turned until the pin is at right angles to the slot, when it is allowed to rest on the roof of the chamber, the spring exerting a downward pressure that holds the base of the chamber firmly in position against the leather flange of the dust-pan. A slot Z in the leather flange fits around the bolt S when the dust-pan is put in position.

From the foregoing description it will be

seen that owing to the novel construction and manner of mounting the one-piece dust-pan and nozzle the danger of leak between these two important members is entirely 5 eliminated; the yielding connection with the body permits the use of wheels under the main body; and to empty the machine of dust and dirt it is only necessary to turn the knob S' one-fourth around, swing the bellows chamber back on its hinges and lift out the dust-laden one-piece pan and nozzle, leaving the machine all the while standing 10 in its natural position on the floor.

The details of construction as herein 15 shown and described constitute what seem to be the best and most practical means of arriving at the ends aimed at, but some of these details could be changed without in the least altering the fundamental novel features of the invention and I therefore do not 20 wish to be understood as confining myself to the exact details herein shown.

claim:—

1. In a vacuum carpet cleaner, a supporting frame-work mounted on wheels in combination with a one-piece nozzle and dust-pan having a yielding detachable connection with the frame-work, a vacuum pump, and an air-chamber having a dust-screen between the nozzle and the inhaling valves of the pump.

2. In a vacuum carpet cleaner, a suitable frame-work in combination with a one-piece nozzle and dust-pan having a detachable 25 air-tight connection with the frame-work, an air pump hinged to the frame and provided with a base with which the dust-pan

is hermetically connected when the pump is in operative position, said base and pan thus forming an air chamber, and means for 40 holding the pump base in air-tight connection therewith.

3. In a vacuum carpet cleaner, a suitable frame-work having a dirt compartment adapted to receive a one-piece dust-pan and nozzle, a hinged connection between the dust pan and walls of the compartment whereby the nozzle is permitted to rest on the floor and caused to move in unison with the machine, and an air chamber and means for 45 exhausting the air from same.

4. In a vacuum carpet cleaner, a suitable frame-work in combination with a one-piece detachable dust-pan and nozzle, an air pump hinged to the frame and provided with a 50 base with which the dust-pan is hermetically connected when the pump is in operative position, said base and pan thus forming an air chamber, said base being adapted to swing back allowing the free removal of 55 the dust-pan and nozzle from the machine.

5. In a vacuum cleaner, the combination of a support, a combined dust-pan and nozzle carried thereby, means for yieldingly connecting said pan and nozzle to the support to permit adjusting movements of the nozzle, and an air pump hinged on the support and adapted when in operative position 60 to be hermetically connected with the dust-pan.
